UNITED STATES PATENT OFFICE.

BEN LEHMAN, OF DAYTON, OHIO.

TOILET-SEAT FOR CHILDREN.

1,156,014.

Specification of Letters Patent.

Patented Oct. 5, 1915.

Application filed February 9, 1915. Serial No. 7,110.

To all whom it may concern:

Be it known that I, BEN LEHMAN, a citizen of the United States, residing at Dayton, in the county of Montgomery and State of 5 Ohio, have invented a new and useful Improvement in Toilet-Seats for Children, of which the following is a specification.

This invention relates to new and useful improvements in toilet seats for children.

10 The principal object of my invention is to provide a seat which may be removably attached to that of a water closet, for comfortably but securely holding a child in place thereon. When a baby has been placed 15 upon the seat, the mother or nurse may thereafter be free to attend to other duties with no fear of danger or inconvenience to the child. The seat may be easily removed from the toilet, and, if desired, maintained 20 in a collapsed position until its further use is necessary.

The preferred form of embodiment of my invention is illustrated in the accompanying drawings, of which—

25 Figure 1 is a perspective view of my invention in position upon a water closet bowl. Fig. 2 is a front view of the device when in position for use. Fig. 3 is a side view thereof. And Fig. 4 is a side view of the seat 30 in a collapsed condition.

Throughout the specification and drawings, similar reference characters denote corresponding parts.

In a detailed description of the preferred 35 form of embodiment of my invention, 1 designates a flat wooden seat having a preferably oval-shaped hole 2 formed in its middle portion. While I have shown the seat 1 as oblong and prefer wood as the material 40 from which it is made, it may be formed in any other suitable shape and constructed of any other suitable material.

The seat 1 is so constructed as to rest upon a seat 3 of an ordinary water closet 45 bowl 4, the hole in the former being smaller than the hole in the last mentioned seat to accommodate a child of tender years.

Suitably secured to and projecting upwardly from, each rear corner edge of the seat 1, is a circumferential metallic band 5. Each of these bands is adapted to loosely receive the projecting ends of a horizontally disposed member 6, preferably circular in cross section. Secured to the horizontal 55 member 6 at right angles thereto, are two

end members 7—7 and a plurality of intermediate slats 8. The members 7—7 and slats 8 are connected to and support a top cross member 9, preferably circular in cross section. The members 6, 7—7, 9 and the 60 slats 8, while preferably constructed of reed, may be made of any other suitable material, and together form a firm but resilient back for the seat 1. (See Figs. 1 and 2).

Extending outwardly from each end of 65 the cross member 9, and beyond the end members 7—7, is a screw 10 which loosely passes through one end of an arm 11 to pivotally support the latter. Suitably secured upon the outer ends of the arms 11, in such 70 a manner as to maintain said arms in approximately parallel relation to each other, is a play shelf 12 embordered by a retaining rim 13. The arms 11 are preferably constructed of reed, while the shelf 12 is preferably made of wood. Upon the latter may be placed toys, or other instrumentalities of 75 amusement for the child.

For the purpose of maintaining the shelf 12 and arms 11 in a horizontal position, as 80 well as firmly securing the seat 1 to the seat 3 of the water closet bowl 4, the following construction is provided. Adapted to be pivotally attached to each one of the arms 11 is a Bessemer steel wire 14 formed as follows. These wires 14 may be constructed 85 of other suitable metal if desired, and as they are similar, a description of one will suffice for a description of the other.

Each wire 14 is bent to parallelism about 90 a point in its extreme middle portion to form two approximately parallel prongs spaced a short distance apart. A short distance from the said middle point, these prongs are bent upwardly at a right angle, 95 and then outwardly at a right angle to form a hook portion adapted to readily receive or grip an inside edge of the seat 3. When an inside edge of the seat 3 is gripped by the hook portion of a wire 14, the upper 100 horizontal prong portions of said wire project a short distance beyond the seat 1, whence they are bent upwardly and outwardly, terminating in looped end portions 105 15—15 which loosely receive one of the arms 11 to be pivotally supported thereby.

Loosely passing through the seat 1, near the middle portion of each marginal side edge thereof, is the shank of a T bolt 16, the T portion of which being adapted to easily 110

pass between the upper horizontal prong portions of its respective wire 14, below the seat 1. When the hook portions of the wires 14 are in a position to firmly grip the inside edges of the seat 1, the T bolt 16 is turned at right angles to its respective wire 14, and by means of a wing nut 17 applied to the upper threaded end of said bolt, the latter may be tightened to press the upper horizontal prong portions of said wire firmly against the bottom of the seat 1, whereupon the latter will be tightly held upon the seat 3, while the vertical portions of said wires will support the arms 11 in a horizontal position. (See Figs. 1 and 3).

Guarded by the shelf 12, arms 11 and the resilient back hereinbefore described, it is impossible for the child to leave the seat 1 after he has been placed thereon.

20 For the purpose of preventing the seat 1 from marring or scratching the seat 3 when placed thereon, rubber feet 18 are preferably secured to the bottom of the first mentioned seat, as shown in Figs. 2, 3 and 4.

25 The seat 1 is applied to the seat 3 in the following manner: First, it is well to pass the T bolts 16 between the upper horizontal prong portions of the wires 14, and then turn the T portions of said bolts at right angles to them. Before the wing nuts 17 are tightened, the hook portions of the wires 14 should be forced inwardly, and then downwardly and outwardly to firmly grip the inside edges of the seat 3. The wing nuts 17 are then turned to draw the upper horizontal prong portions of the wires 14 tightly against the bottom of the seat 1, thus rigidly maintaining the hook portions of said wires in a position to hold the seat 1

40 firmly upon the seat 3. When so maintained, the upwardly and outwardly projecting portions of the wires 14 will firmly support the arms 11 and the shelf 12 in a horizontal position to prevent the child from leaving the seat 1. Furthermore, the play shelf 12 is provided to occupy the mind of the child while in place upon the seat, thus making it possible for the mother or nurse to attend to other duties while the child is so engaged.

45 After use, the device may be collapsed as follows. The wing nuts 17 are loosened, the hook ends of the wires 14 disengaged from the seat 3, and the T portions of the bolts 16 turned to a position to release the prong portions of said wires. The arms 11 are then elevated to raise the hook ends of the wires 14 above the seat 1, whereupon said hook ends are moved inwardly between said arms, to permit the latter to descend to the position shown in Fig. 4. In its collapsed condition the device may be readily carried about, and kept within a small space.

50 I do not wish to be limited to the details of construction and arrangement herein

shown and described, and any changes or modifications may be made therein to suit different conditions of use.

Having described my invention, I claim:

1. A toilet seat for children, comprising a bottom member having a hole formed therein, back, front and side guards above said member, and means connected to said side guards and bottom member for firmly securing said seat to that of a water closet, substantially as described. 70

2. A toilet seat for children, comprising a bottom member having a hole formed therein, an upright back member secured to said bottom member, arms secured to, and extending forwardly from the upper portion of said back member, a cross member secured to the forward ends of said arms, fastening devices pivotally depending from said arms, below said seat, and clamping means on said bottom member, adapted to engage said fastening devices and firmly secure them in an adjusted position, substantially as described. 80

3. A toilet seat for children, comprising a flat bottom member having a hole formed in its central portion, a back member hingedly secured to said bottom member, arms pivotally secured to and extending forwardly from the top portion of said back member, a cross member secured to the front ends of said arms, a fastening device pivotally depending from each of said arms, and terminating in a hook-shaped portion adapted to grip the edge of a water-closet seat, and a clamp secured to each side of said bottom member, to engage and firmly lock said fastening devices in an adjusted portion, substantially as described. 90

4. A toilet seat for children, comprising a flat bottom member having an oval-shaped hole formed in its central portion, a back member hingedly secured to said bottom member, arms pivotally secured to and extending forwardly from the upper portion of said back member, a shelf secured to the outer ends of said arms, a pair of fastening wires, each of said wires being bent to parallelism at its middle portion to form two parallel prongs, said prongs being in turn bent upwardly, outwardly and thence upwardly, terminating in two looped end portions adapted to loosely receive one of said arms, and thus be pivotally supported thereby, and an adjustable device adapted to extend between and below the horizontal prongs of each wire, to tightly clamp the latter against the bottom member, substantially as described. 100

5. A toilet seat for children, comprising a flat bottom member having an oval-shaped hole formed in its central portion, a back member hingedly secured to said bottom member, arms pivotally secured to and extending forwardly from the upper portion 110

of said back member, a shelf secured to the outer ends of said arms, a pair of fastening wires, each of said wires being bent to parallelism at its middle portion to form two parallel prongs, said prongs being in turn bent upwardly, outwardly and thence upwardly, terminating in two looped end portions adapted to loosely receive one of said arms and thus be pivotally supported thereby, and a T bolt extending from each

side of said bottom member, between and below the horizontal prong portions of each wire to engage the latter and clamp it in an adjusted position, substantially as described.

In testimony whereof I have hereunto set 15
my hand this 8th day of February, 1915.

BEN LEHMAN.
